COMBINATION BOOK RACK AND HOLDER FOR COMMUNION CUPS FOR A PEW RACK

Willis E. Davis, Waco, Tex., assignor to L. L. Sams &
Sons, Inc., Waco, Tex., a corporation of Texas

Filed July 13, 1961, Ser. No. 65,910

Term of patent 14 years

(Cl. D33—3)

FIGURE 1 is a perspective view of a combination book rack and holder for communion cups for a pew back showing my new design.

I claim:

The ornamental design for a combination book rack and holder for communion cups for a pew back, substantially as shown.
